CLAIM

The ornamental design for a set of wheels and hubs for a toy vehicle, as shown and described.

DESCRIPTION

FIG. 1 is a front perspective view of a toy vehicle with wheels and hubs.

FIG. 2 is a side view of the vehicle of FIG. 1. The opposing side view is a substantial mirror image of the side view shown in FIG. 2.

FIG. 3 is a front perspective view of the wheels and hubs of FIG. 1; and,

FIG. 4 is rear perspective view of the wheels and hubs of FIG. 1.

The broken or dashed lines shown in the drawing are for illustrative purposes only and form no part of the claimed design.

The drawings are lined for color, with vertical parallel denoting the colors red or pink.

The shading lines shown in the drawing represent the three-dimensional contour of the design, and are not intended to indicate surface decoration.
